UNITED STATES PATENT OFFICE

165,508

RADIO CABINET

Robert D. Budlong, Skokie, Ill., assignor to
Zenith Radio Corporation, a corporation of
Illinois

Application August 17, 1951, Serial No. 16,322

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio Cabinet, of which the following is a specification, reference being made to the accompanying drawings, forming a part thereof:

Figure 1 is a perspective view of the radio cabinet showing my new design with the cover open, and

Figure 2 is a perspective view of the radio cabinet showing my new design with the cover closed.

The side of the cabinet not shown is identical with that shown and the rear of the cabinet is plain.

I claim:

The ornamental design for a radio cabinet, substantially as shown and described.

ROBERT D. BUDLONG.
